US0D1004784S

(12) **United States Design Patent** (10) Patent No.: **US D1,004,784 S**
(45) Date of Patent: ** Nov. 14, 2023

(54) **ULTRASOUND SCANNER**

(71) Applicant: **Clarius Mobile Health Corp.**,
Vancouver (CA)

(72) Inventors: **Binda Zhang**, Surrey (CA); **Daniel Christian Rahardja**, Burnaby (CA);
Kris Dickie, Vancouver (CA); **Laurent Pelissier**, North Vancouver (CA)

(73) Assignee: **Clarius Mobile Health Corp.**,
Vancouver (CA)

(**) Term: **15 Years**

(21) Appl. No.: **29/794,421**

(22) Filed: **Jun. 11, 2021**

(51) LOC (14) Cl. **24-02**

(52) U.S. Cl.

USPC **D24/187**

(57) **CLAIM**

The ornamental design for an ultrasound scanner, as shown and described.

DESCRIPTION

FIG. 1 is a front perspective view of an ultrasound scanner in accordance with the present design;

FIG. 2 is a rear perspective view thereof;

FIG. 3 is a top view thereof;

FIG. 4 is a front view thereof;

FIG. 5 is a right side view thereof;

FIG. 6 is a left side view thereof;

FIG. 7 is a rear view thereof; and,

FIG. 8 is a bottom view thereof.

The broken lines in the figures depict portions of the ultrasound scanner that form no part of the claimed design.

1 Claim, 4 Drawing Sheets
